Herbert B. Krueger, 5570 SW. 91st Ave., Portland, Oreg.

Filed July 7, 1958, Ser. No. 51,673

Term of patent 14 years

(Cl. D52—6)

Fig. 1 is a front elevation of a combination fuel tank measuring gauge and sampler, showing my new design;

Fig. 2 is a rear elevation of the combination fuel tank measuring gauge and sampler, showing Fig. 1;

Fig. 3 is a sectional view taken along the line 3—3 in Fig. 1;

Fig. 4 is a sectional view taken along the line 4—4 in Fig. 1; and

Fig. 5 is a bottom plan view as viewed upwardly from the bottom in Fig. 1.

Figs. 1 and 2 of the drawings are shown broken away to indicate indeterminate length. In Fig. 2 a portion of the chain and the handle have been omitted for convenience of illustration.

I claim:

The ornamental design for a combination fuel tank measuring gauge and sampler, as shown and described.
